UNITED STATES PATENT OFFICE.

MARY HEATH, OF NEW YORK, N. Y.

CORSET.

No. 907,232.

Specification of Letters Patent.

Patented Dec. 22, 1908.

Application filed May 18, 1906. Serial No. 433,367.

To all whom it may concern:

Be it known that I, MARY HEATH, a citizen of the United States, residing at New York city, Manhattan borough, county and State of New York, have invented certain new and useful Improvements in Corsets, of which the following is a clear, full, and exact description.

This invention relates to an improved corset, the object being to provide a corset that will be flexible in the parts embracing the region of the lungs or chest cavity, thereby permitting of a free respiratory movement and induce deep breathing. While my improved corset is designed for flexibility at the above named portion or top thereof, it is also adapted for flexibility at the waist line, and comparative rigidity at the hip portion. The flexible nature of my improved corset affords support for the bust and abdomen without exerting any undue pressure upon the said parts.

In connection with the rigid portion of my improved corset, that is to say, the hip portion, I employ an elastic abdominal bandage which is attached to the corset, at the rear thereof, and is adapted to pass around the body, over the hips, and clasp together under the lower abdominal cavity. The bandage which I employ is designed to exert a lifting force upon the abdomen and tend to raise it and force the parts backward into their proper place within the said cavity. The flexibility of the corset permits the bandage to raise the abdomen; that is to say, the front of the corset does not bind the abdomen and thus prevent the bandage performing its intended function.

The action of my improved flexible corset together with the bandage carried thereby is just the reverse of the ordinary corset which, when clasped, forces the abdomen downwardly and inwardly, thereby causing discomfort to the wearer in the event of prolapsus of any of the adjacent organs. For the relief of prolapsus of the organs in the region of the abdomen, the abdomen is usually lifted away from the affected parts. For these purposes my improved corset and bandage are well adapted.

My improved corset is sufficiently flexible and adjustable to be worn during maternity. As my improved abdominal bandage tends to raise and press inwardly the intestines, thereby reducing the abdomen, tight lacing is obviated.

To aid in reducing the hips I provide the corset with extended flexible portions, at the sides thereof, the said portions being adapted to extend over the hips and thighs. At the lower end of the said extensions I attach hose supporters, which, when attached to the hosiery, pull the extensions downwardly, whereby the flesh over the hips is flattened. The action of the side extensions also aids in supporting the abdomen.

A detailed description of my improved corset will now be given, and the features thereof finally claimed, reference being had to the accompanying drawing, wherein—

Figure 1 is a perspective view, looking from the front, of my improved corset; Fig. 2 is a similar view, looking from the rear; and Fig. 3 is an enlarged detail view of one member of my improved bandage, with which the corset is provided.

Referring to the drawing, 1 in Fig. 1 indicates the front, right hand section of my improved corset, while 2 indicates the front left hand section.

Referring to Fig. 2, 3 and 4 indicate the back sections. The sections 1 and 4 are adjustably connected by a lacing 5, which is manipulated in the usual manner (see Fig. 1), the sections 2 and 3 being likewise connected by lacing 6 (see Fig. 2). The front sections 1 and 2 are adapted to clasp together, as at 7, in the usual manner. The back sections 3 and 4 are adjustably connected by a lacing 8.

It will be seen, in Figs. 1 and 2, that my improved corset is made in halves A and B, the said halves being connected by the lacing 8 to form the complete corset. Each of the halves, A and B are partially severed, as at 9 and 10, respectively, thereby forming gaps, the said gaps being spanned by the aforesaid lacings 5 and 6. The gaps 9 and 10 extend downwardly and end a little below the hip region, as indicated by 11 and 12. The said sections A and B terminate, at the lower ends thereof, in hip-pads 13 and 14 respectively, the said pads being provided with hose-supporting straps 15 and 16, respectively. To the half A, at the rear thereof, I attach as at 17, the elastic members 18 and 19 of the section C of my improved abdominal bandage. The said member C passes over and around the half B, as shown and terminates in a non-elastic tab 20, which in this instance is provided with a button-hole 20. To the half B, I attach, as at 21, the

105
110

other section D of my improved bandage, the said section D comprising the elastic members 22 and 23 which pass through a portion of the back of the half A of the corset, as shown by 24 (Fig. 2), then over and around the said half A to the front thereof. The members 22 and 23 terminate in a non-elastic tab 25, which is provided with a button 26 adapted to engage the button-hole 20^a 5 in the tab 20 of the member C. The tabs 20 and 25 are sufficiently long, and wide enough to approximately cover the abdominal region, the resiliency being provided by the elastic members 18, 19, 22 and 23.

10 It is obvious from the foregoing description, and the drawing, that the halves A and B of the corset comprise a unitary hip pad and a plurality of adjustable elastic sections adjacent thereto. It may here be stated that 15 the hip pads or extensions 13 and 14 are preferably flexible, that is to say, they are not stiffened, being simply extensions of the material of the corset, such as silk for instance. The hip-pads or extensions may be integral 20 with the body of the corset, or they can be attached.

One of the features of my improved corset 25 is to provide a non-yieldable bandage for the hips and thighs, and a yieldable upper or bust-supporter. To gain this end I have 30 constructed the halves of the corset, as hereinbefore described, with a yieldable portion and a non-yieldable portion, the non-yieldable portion being reinforced by a resilient 35 abdominal bandage.

It is quite evident that I can adjust the sections 1, 2, 3 and 4 to fit the body, by means

of the lacings 5, 6 and 8. The portion of the corset above the waist line can be regulated, due to the plurality of sections, without materially affecting the waist line or hip portion.

The purpose of forming the abdominal bandage as hereinbefore described, viz., of two independent elastic members, is to adapt 45 the said bandage to accommodate itself to the shape of the hip without wrinkling.

Having now described my invention, what I claim and desire to secure by Letters Patent is:

A corset comprising the halves A and B severed throughout a portion of their length, the half A being provided with a hip-pad 13, and the half B being provided with a hip-pad 14, said halves being non-yieldable 55 adjacent to said hip-pads, an abdominal bandage carried by said corset, said bandage comprising two independent elastic members C and D, the member C being secured to the corset half A, and the member D being secured to the corset half B and adapted to pass through an opening 24 in the corset half A, said abdominal bandage members being composed of a plurality of elastic members 60 adapted to pass around the corset, and clasping means carried by said bandage members at the free end thereof.

Signed at New York city, N. Y., this 14th day of May, 1908.

MARY HEATH.
